UNITED STATES PATENT OFFICE.

JULES BYRON TAYLOR, OF TOLEDO, OHIO.

GEARING.

1,387,813.

Specification of Letters Patent. Patented Aug. 16, 1921.

Application filed August 13, 1919. Serial No. 317,168.

To all whom it may concern:

Be it known that I, JULES BYRON TAYLOR, a citizen of the United States, and a resident of Toledo, in the county of Lucas and State of Ohio, have invented a certain new and useful Gearing; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to control means for gearing of the automatic reversing type, such, for instance, as is used in connection with the operation of a washing cylinder of a washing machine.

20 The primary object of my invention is the provision of improvements in the automatic control for the reversing means and in the manually controlled stop means for such mechanism disclosed in former United States Letters Patent, No. 1,170,707, dated February 8, 1916, whereby a more perfect and satisfactory operation of the mechanism is obtained.

25 The invention is fully described in the following specification, and while, in its broader aspect, it is capable of embodiment in numerous forms, a preferred embodiment thereof is illustrated in the accompanying drawings, in which,

30 Figure 1 is a front elevation of a gearing embodying my invention with parts broken away and with the shiftable clutch member in neutral position. Fig. 2 is a central vertical section of the mechanism with the connected operated parts fragmentarily shown. Fig. 3 is an enlarged perspective view of the automatic reversing link, and Fig. 4 is an end elevation of the manually controlled clutch shifting member in engagement with a stop member and shown in released position by dotted lines.

35 Referring to the drawings, 1 is a drive shaft provided with a suitable drive means. This shaft is journaled in bearings on the machine at opposite sides of the circular casing 2, which is suitably secured to the front of the machine and incloses the reversing gearing. Upon the shaft 1 is a sleeve 3 movable longitudinally thereof but 40 rotatable therewith by reason of a pin and groove 3^a or other suitable connection there-

between. At each end of the sleeve 3 and rigid therewith is a clutch member 4 adapted to engage a corresponding clutch member 5 rigidly connected with or forming a part of 45 bevel pinions 6 loose upon the shaft 1. It will be seen that as the sleeve is moved longitudinally the members of one or the other of the clutches will be operatively connected according to the direction in which the 50 sleeve is shifted.

A driven shaft 7, at right angles to the shaft 1, is journaled in the inner side of the case 2 and is connected at the end thereof most remote from the shaft 1 to the member 8, which it is desired to operate, which, in the present instance, is the washing cylinder of a washing machine. At its other end, the shaft 7 is fixedly connected to the center of a dish-shaped gear wheel 9, the 55 beveled teeth of which are arranged around its outer edge and mesh with both pinions 6. Upon the face of the gear 9 next to the sleeve 3 is a spiral groove 10 extending from near its center to near the rim of the 60 gear, the bottom of the groove at its outer end sloping outwardly, as shown at 11, to provide a slightly elevated return communication with the groove of the next convolution. The purpose of this will be hereafter 65 described.

The groove 10 is engaged by a pin 12 projecting from one end of the lever 13 fulcrumed, as at 14, upon a bracket 15 bolted or otherwise rigidly secured inside of the 70 casing 2 at its lower side. The opposite end of the lever 13 is pivotally connected at 16 with one end of a link 17, the other end of which projects transversely therefrom and is provided with an elongated longitudinally 75 extending slot 18. A lever 19 is fulcrumed to the bracket member 15 or casing 2 at 20 and is provided with a pin 21, which projects into the slot 18 of the link 17 for predetermined lost motion movement therein to 80 permit a limited rocking of the lever 19 without effecting a movement of the link 17, or vice versa. The lever 19 is recessed at its inner or fulcrumed end, as at 22, to loosely receive the lower end of a lever 23 85 fulcrumed, as at 24, upon the bracket 15. The upper end of the lever 23 is notched to straddle or embrace a peripheral rib or ring 25, which encircles and is rigidly carried by the clutch sleeve 3 intermediate its 90 ends.

A weight 26 is carried by the lever 19, and

in the present embodiment of the invention this weight is pivotally suspended from the lever near its upper or free end and has a recess in its side to receive the lever with the sides of the recess forming stops which limit the swing of the weight relative to the lever.

The permissible movement of the pin 21 of the weight lever 19 within the link slot 18 longitudinally thereof is controlled by stop-pins 27 and 28, which are inserted through bosses or lugs 29 and 30 at the inner and outer ends, respectively, of the slot 18. The pins 27 and 28 are adjustable toward and away from each other lengthwise of the slot 18 and coat with the pin 21 to limit the length of either swinging stroke of the lever 19. Screws 27^a and 28^a are threaded in the respective bosses 29 and 30 to engage 20 and secure the stop-pins 27 and 28 in adjusted positions.

The manual control for shifting the clutch sleeve 3 comprises a rod 31, which is mounted for longitudinal movements in the case 2 parallel to the shaft 1, and in the present instance, at the upper side thereof. The rod 31 carries a sleeve 32 within the case 2, for limited rotary movements, and this sleeve has a forked arm 33 extending downward therefrom with the forks thereof disposed at opposite sides of the rib or ring 25 on the sleeve 3 and with the ends of the fork arms bifurcated to straddle the sleeve 3. The rocking movements of the rod 31 relative to the sleeve 32 are limited by a pin 34, which projects through the rod and has engagement at its opposite ends with opposite sides of a stop lug 35, on the sleeve end, as best shown in Fig. 4. One end of the rod 31 is provided with a lateral extension 36, which, when disposed in the reclining position shown in Figs. 1 and 4, rests on a catch finger 37 that projects horizontally in an adjustable manner from a stationary casing or frame part 38. This finger 37 has a notch in its top surface into which the angled end or extension 36 of the rod 32 drops when in register therewith. The notch in the catch finger 37 is so disposed that when the rod 50 extension is engaged therewith the clutch sleeve 3 is in its neutral or released position as shown in Fig. 1. When the rod has been rotated to place the extension 36 in the upright dotted line position shown in Fig. 54, it will maintain such position and permit a continuous automatic operating of the gearing until the control rod has been turned by hand to permit its extension 36 to engage the notched catch finger 37.

60 A screw 39 connects the arms of the fork 33 to permit adjustment thereof toward or away from each other to adapt them to fit the rib 25 and to compensate for wear.

65 The operation of the mechanism is as follows: To start the machine, the operator

turns the control handle 31 to place the extension 36 thereof in elevated position, as shown by dotted lines in Fig. 1, and the gravity action of the weight 26 automatically acts through the levers 19 and 23, to move 70 the clutch sleeve 3 into engagement with one or the other of the two pinions 6. With the lever 19 in the position shown in Fig. 1 the clutch sleeve 3 will be moved into clutch engagement with the left-hand pinion 6 thereby by driving said pinion in a direction to impart a counter clockwise rotation to the gear 9. This movement of the gear 9 causes movement of the upper end of the lever 13 toward the center of said gear due to the pin 12 of 80 said lever traveling in the spiral groove 10. This movement of the lever imparts a pull to the left on the link 17, the pin 28 of which is now in engagement with the pin 21 on the lever 19 so as to gradually move said lever 85 toward upright position. When the lever 19 has been moved sufficiently to pass a vertical plane, the action of the weight 26 will cause it to quickly rock to the extent of its movement to the left, thereby operating the 90 lever 23 to shift the clutch sleeve 3 out of engagement with the left hand pinion 6 and into engagement with the right hand pinion 6. The right hand pinion 6, which is now the live pinion, will cause a driving of the 95 gear 9 in clockwise direction so as to cause an outward traveling of the pin 12 in the groove 10. When the lever 13 has been rocked a predetermined distance in the outward movement of the pin 12, the pin 27 on 100 the link 17 will have engaged and moved the lever 19 past vertical position to permit its weight to then act to quickly operate the lever to effect a shifting of the clutch sleeve 3 to effect a reversing of the movement of 105 the gear 9. This is repeated so long as the control rod 31 is left in its operative position. When it is desired to stop the machine, the rod 31 is turned to permit the extension 36 thereof to rest on the catch finger 37 and 110 upon the next shifting of the clutch sleeve 3 the extension 36, when said sleeve is in its neutral or released position, as shown in Fig. 1, will drop into the catch notch of the finger 37 and hold the parts against further 115 movement.

The purpose of the pins 27 and 28 in the link 17 is to not only maintain an accurate operation of the parts, but also to permit an adjustment of each end wall of the link slot 120 to effect an early or late tripping of the weight lever 19 at each inward and outward stroke of the spiral groove engaging end of the lever 13 so that a reverse movement of the cylinder 8 or actuated member may be 125 obtained at the end of a desired or predetermined number of revolutions thereof, which is found to be quite an important item in machines of the character described. Should the link 17 or other control parts be- 130

come broken so that the clutch sleeve 3 is not shifted upon an outward movement of the pin 12, in the spiral groove 10, the gear 9 will continue its rotation and the pin 12 when at the end of the groove will be directed over the elevated bottom portion 11 thereof back into the front end of the last of the outer convolutions of the groove. This is repeated until the machine is stopped 10 by hand, or if it is desired to continue the running of the machine the control rod 31 is moved by the operator first in one direction and then the other at desired intervals to shift the clutch sleeve 3 and cause the cylinder to be successively driven in first one direction and then the other.

I wish it understood that my invention is not limited to any specific construction, arrangement or form of the parts, as it is 20 capable of numerous modifications and changes without departing from the spirit of the claims.

Having thus described my invention, what I claim as new, and desire to secure by Letters Patent, is,—

1. In a mechanism of the class described, a disk having in its side a spiral groove, a gear wheel connected to said disk and operable when rotated to impart rotation to 30 said disk, a drive shaft having constant rotation in one direction, pinions loose on the shaft and in mesh with the gear wheel at opposite sides of its axis, a clutch member adapted to operatively engage either of said 35 pinions with said shaft, a shifter element operable to move said member to engage first one and then the other of said pinions, a movable gravity member operable when at a predetermined point in its movement in 40 either direction to act by gravity on said element to effect a shifting thereof, a lever having a part traveling in the groove of said disk, a link connected to the lever and having a longitudinally extending slot therein 45 in which a part of said gravity member works whereby a tipping of the gravity

member in one direction or the other to gravity operating position is effected by a movement of said link first in one direction and then the other, and members adjustably 50 carried by the link at the ends of its slot to vary the permissible relative movement of the gravity member relative to the link.

2. In a mechanism of the class described, a gear wheel, a drive shaft, pinions loose on 55 said shaft and engaging said wheel at opposite sides of its axis, a clutch means operable to engage either of said pinions with said shaft, means operable by a rotation of said gear wheel to periodically move said clutch 60 means to engage first one and then the other of said pinions, a control member mounted for both longitudinal and rotary movements, said member having a part in engagement with said clutch means, a catch member for 65 engaging said control member when the latter is in one position of its rotary movement and at a predetermined point in its longitudinal movement to coact therewith to hold the clutch means in neutral position. 70

3. In a mechanism of the class described, the combination with a clutch member which is automatically shiftable at predetermined intervals to engage first one and then another drive pinion, a control rod mounted for 75 rotary movements relative to said clutch member and for longitudinal movements therewith, said rod having a laterally projecting part, means carried by said rod in engagement with said clutch member to 80 cause the two to have longitudinal movements together, a catch member having a notch therein with which the laterally projecting part of said rod, when at one position of its rotary movement and at a predetermined point in its longitudinal movement 85 may engage and coact therewith to hold the clutch member in neutral position.

In testimony whereof I have hereunto signed my name to this specification.

JULES BYRON TAYLOR.
